US00D845952S

(12) **United States Design Patent** (10) Patent No.: **US D845,952 S**
(45) Date of Patent: **** Apr. 16, 2019**

(54) **SCANNER**

(71) Applicant: **BROTHER INDUSTRIES, LTD.**,
Nagoya-shi, Aichi-ken (JP)

(72) Inventor: **Keiichiro Egami**, Kuwana (JP)

(73) Assignee: **BROTHER INDUSTRIES, LTD.**,
Nagoya (JP)

(**) Term: **15 Years**

(21) Appl. No.: **29/640,098**

(22) Filed: **Mar. 12, 2018**

(30) **Foreign Application Priority Data**

Oct. 31, 2017 (JP) 2017-024248
(51) LOC (11) Cl. **14-02**

CLAIM

The ornamental design for a scanner, as shown and described.

DESCRIPTION

FIG. 1 is a perspective view of a scanner;
FIG. 2 is a front view thereof;
FIG. 3 is a top view thereof;
FIG. 4 is a left-side view thereof;
FIG. 5 is a right-side view thereof;
FIG. 6 is a rear view thereof;
FIG. 7 is a bottom view thereof; and,
FIG. 8 is perspective view thereof with a cover and a paper
guide in an opened position.
The evenly spaced broken lines depict environmental sub-
ject matter only and form no part of the claimed design.

1 Claim, 7 Drawing Sheets
